UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,299,939.

Specification of Letters Patent.

Patented Apr. 8, 1919.

Application filed November 22, 1917. Serial No. 203,317.

To all whom it may concern:

Be it known that I, DAVID W. HAWKSWORTH, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates to car roofs of that type in which the carlines are arranged above the roofing sheets and form the supports and weather proofing caps therefor. The present invention has particular reference 15 to various features of construction as hereinafter set forth.

In the drawings:

Figure 1 is a cross section through the car;

20 Fig. 2 is an enlarged section through one end of the carline showing the means for supporting and attaching the same to the side plate of the car;

Fig. 3 is a plan view of Fig. 2 partly in 25 horizontal section;

Fig. 4 is a side elevation;

Fig. 5 is a cross section through the center 30 of the carline showing the weather proofing joint for the sheets and the manner of supporting the running-board saddle;

Fig. 6 is an end elevation of the running-board saddle; and

Fig. 7 is a plan view thereof.

35 A are the carlines of inverted U cross-section, having laterally-extending flanges at their lower ends, said carlines being arched transversely of the car and having downturned end portions B overlapping the side of the car. C are the roofing sheets arranged beneath the carlines, and which are provided at their side edges with upturned flanges D returnbent and nested, and being arranged within the channel of the carline. E are hanger bolts engaging slotted bearings

40 F within the carlines and passing downward through apertures in the nested flanges D. G are bearing blocks mounted on the hangers E and engaging the nested flanges, and H are nuts having a threaded engagement 45 with the lower ends of the hangers and supporting the blocks G.

The construction as thus far described is similar to roofs heretofore used and when applied to the car body the downturned portions B of the carlines are bolted to the side 55 plates of the car. It is necessary, however, to space these downturned ends from the sides of the car to provide clearance for downturned eaves flanges on the roofing sheets, and where the side plate of the car is 60 formed of wood they do not provide a rigid support for the carline bolts. I have therefore devised a construction in which a more rigid support is afforded as follows:

I is a metal member preferably of angle 65 cross section, one flange of which rests upon the top of the side plate J, while the other flange I' overlaps the outer side of said plate. K is a metallic block forming a spacer between the member I and the downturned portion B of the carline, and L are 70 bolts passing through the flanges of the carline, the block K and the side plate J, to clamp the carline in position. To relieve the bolts from shearing stress and to form 75 an additional support for the carline, a lug L', preferably formed of pressed sheet metal, is arranged to fit within the channel of the carline, to which it is suitably attached as by rivets L². This lug has a portion ex- 80 tending inward to overlap and rest upon the block K, and consequently the load upon the carline is largely transmitted through the lug L' to the block K. The block K in addition to the securing of the bolts L is 85 preferably riveted to the flanges I, as indicated at M, so that the load carried into the block from the lug L' is in turn carried into the flange I' of the member I and from the latter into the top of the plate J.

90 The lug L' in addition to its mechanical function as a support performs the further function of an additional weather-proofing means for stopping the channel of the carline and preventing the rain from beating upward into the portion overlying the car. A further weather-proofing is effected by a flashing plate N, which has a flange N' overlapping the siding O of the car body and also having a depressed panel N² which 100 passes between the block M and the flange I', being bent inward at its upper end to

5 partially overlap the rounded corner of the member I. Thus any water that may find access to the channel of the carline through the joint between the same and the roofing sheets will be directed by said sheets beyond the flashing N and by the latter will be conducted outside of the car.

10 During operation the roofing sheets will be moved relative to each other and to the carlines to compensate for weaving stresses in the car frame. This causes more or less abrasion at the points of contact with the carline flanges, particularly where cinders are driven into the joint, and thus there is 15 danger of destroying the weather-proofing coating of the sheets so that they will rust. I have avoided this defect by placing a non-metallic bearing, preferably formed of felt, between the flanges of the carlines and the 20 sheets, the material extending over the nested flanges D, as indicated at P. This member therefore forms additional weather-proofing as well as a non-metallic bearing.

25 The running-board saddle may be attached directly to the carline, as the latter is above the roofing sheets. Inasmuch, however, as the carline is of arch form it is necessary either to form the saddle of a similar curvature or to provide other means for the 30 proper bearing. This I have accomplished by forming a saddle of folded sheet metal comprising top portion Q with the returnbent flanges Q' and downturned flanges Q² which embrace the sides of the carline. The 35 top portion Q extends in the same plane from end to end of the carline, but at the center of the ends there is a depressed portion R, as shown in Fig. 6, curved to fit the cross section of the carline and sufficiently 40 depressed to support the ends of the saddle when its center is resting upon the arch. The returnbent flanges are provided with a suitable number of apertures S for the engagement of securing bolts for the running 45 boards, and the saddle itself is secured to the carline by suitable means, such as rivets T.

What I claim as my invention is:

1. In a car roof, the combination with a 50 carline of inverted channel section and having a downturned end portion overlapping the eaves, of a lug secured within the channel of the downturned portion and projecting inward beyond the same, and a member supported on the plate of the car forming a seat for said lug.

2. In a car roof, the combination with a 60 carline of inverted channel cross section having a downturned end portion for overlapping the eaves, of a lug secured within the channel of the downturned portion and projecting inward therefrom, a member resting upon the side plate of the car and projecting downward on the outer face thereof,

65 a second member upon said first-mentioned member and a seat on said second member for engaging and supporting said lug.

3. In a car roof, the combination with a carline of inverted channel section with laterally-extending flanges and having a 70 downturned portion overlapping the eaves, of a member resting upon the side plate of the car having a downturned portion on the outer face of said side plate, a member secured to said downturned portion forming a 75 spacer between the same and the flanges of the downturned portion of said carline, and a lug fitting and secured within the channel of the downturned portion of the carline, projecting inward therefrom and resting 80 upon said spacer.

4. In a car roof, the combination with a carline of inverted channel section having laterally-extending flanges and provided with a downturned end portion of similar 85 section overlapping the eaves of the car, of a metallic angle member having one flange thereof resting upon the side plate of the car and a downturned flange lying adjacent to the outer face of said side plate, a member 90 secured to said downturned flange forming a spacer between the same and the flanges of the downturned portion of the carline, securing bolts for the carline passing through the downturned flanges thereof, 95 the spacer and the side plate of the same, and a lug secured within the channel of the downturned portion of the carline projecting inward therefrom and resting upon said spacer.

100 5. The combination with a wooden side plate, of a carline of inverted-U cross section having laterally-extending flanges provided with a downturned end portion overlapping said side plate, a metallic angle member having one flange resting on said side plate and a downturned flange adjacent to the outer face thereof, a member secured to said downturned flange forming a spacer between the same and the flanges of the 105 downturned portion of said carline, bolts passing through the downturned flanges of the carline, said spacer, metallic angle member and the side plate, and a lug fitting 110 within the channel of the downturned portion of the carline and secured thereto, said lug projecting inward and resting upon said spacer.

115 6. The combination with a wooden side plate, of a carline of inverted-U cross-section having laterally-extending flanges provided with a downturned end portion overlapping said side plate, a metallic angle member having one flange resting on said side plate and a downturned flange adjacent 120 to the outer face thereof, a member secured to said downturned flange forming a spacer between the same and the flanges of the 125

downturned portion of said carline, bolts passing through the downturned flanges of the carline, said spacer, metallic angle member and the side plate, a lug secured within 5 the channel of the carline and projecting inward and resting upon said spacer, car siding secured to said side plate below and at

the sides of said metallic angle plate, and a flashing secured between the downturned flange of said angle plate and said spacer 10 and bent outward to overlap said car siding beneath and at the sides thereof.

In testimony whereof I affix my signature.

DAVID W. HAWKSWORTH.
